C. Bassett Sheet 1-3 Sheets.

Dressing Leather
Patented Mar. 25, 1835.

Fig. 1. Plan.

Cushman Bassett of Boston Massachusetts

Letters Patent

The Schedule referred to in these Letters Patent and making part of the same containing a description in the words of the said Cushman Bassett himself of his improvement called the Leather Dresser

It all persons to whom these presents shall come. Cushman Bassett of Boston in the County of Suffolk and State of Massachusetts. Greeting. Be it known that I the said Cushman Bassett have invented constructed made and applied to use a new and useful improvement in the art of finishing Morocco and Kid Skins, beating Goat and other skins, staining and graining commonly called Boarding Skins, also for working all kinds of leather used in ouried leather, and finishing the same, which I call the Leather Dresser. And my invention and improvement is by me fully specified and described in the words and figures following "to wit": I make a platform on which the operator stands on the front part of which are two boards inclining obliquely before him at a convenient height for his operation. the one ^{of that} stationary, and the other movable in the manner herein after described, and as is represented in the model and drawings herewith presented. On the stationary board a Run is made to pass, with a Brush, Roller, or hard piece of wood at the end of it at the pleasure of the operator over the leather to be finished, which leather must be moved from place to place during the operation of finishing, at the pleasure of the operator, who will manage and move the leather and place it under the Roller by manipulation. The movable board is made to move by the machinery, hereafter described as represented in the Model and drawings herewith sent. and it is for the same purpose of finishing skins by polishing them in a different mode, under the management of the operator, all of the said modes are fully described in the model and drawings herewith sent and herein described. The object of this invention is to give the operator in finishing the skins and various preparations of leather as aforesaid the power to poised and effect his work by exact mechanical

operation with much greater perfection and with more facility than could be done in any of the ordinary modes of manipulation heretofore known or used. My machine is constructed as follows, to wit, to make a platform on the floor of the length of fifteen feet and six feet wide, or any ^{other} desirable length or width, of plank Timber or any other suitable material mounted on the plan A from the four corners of the platform are four strong posts marked B. of suitable material, which are secured by strong frame timber at or near their tops, or they may when convenient pass by these timber and be firmly inserted into the timber of the floor above. The frame timber at the top are marked, the two end ones C.C. and the two side ones C.C. The end frame timber C.C. support the cylinder D. which is made by guides at the end to revolve on suitable metallic grooves or fastenings on said timber. By the application of power to the crank marked a, or the drum on the shaft marked b.b. The cylinder D may be made a continued drum, of suitable size as presented in the model and drawings, or it may be a metallic shaft with ~~the~~ rings on it, to carry the bands marked C.C., and from this cylinder the power is transmitted to carry the whole of the machinery. It is the stationary working board or plank. Standing at an angle of about forty-five degrees, well secured on the platform at the bottom and supported behind by any suitable braces or supports. It is a moveable working board or plank placed at a similar angle moved by the machinery herein after described, and sliding at the bottom on the groove marked d, and at the top on a rail raised and secured in any convenient manner. These boards may be of any desired thickness or dimensions at the pleasure of the operators. The dimensions of these and all other parts as appear to me convenient are represented in the model and drawings. Behind the board the operators stand to manage the skins and materials to be wrought. G.G.G. are planches made of strong wood or other materials sufficiently braced, that project two of them form the back upright parts and the other form the back upper frame timber, for the purpose of supporting the cylinder drums and double cranks to carry the shafts or plungers on the ends of which are placed the Rollers Brushes hand

pieces of wood, slickers or other substances for finishing the work. But they may well and perhaps with advantage be dispensed with, by placing the cylinders, Drums and double Cranks for carrying the shafts, above said a little lower and directly between the rear upright posts, for the accommodation of which operate the cylinder D. with the cross timber, that support it, may be placed as much higher, as may be required. Bands or straps of leather or any other suitable material marked c.c. pass over the drum D and the drums H.H. to carry the machinery. The drums H.H. are fastened on the shafts II. One of each of said drums, is to be used when the machinery is at work, and the other when it is at rest. The shafts I.I. may be coupled together at their central point of meeting at G. or left unconnected there and used separately. The figures 5.5. are double cranks on the shafts II. J.J. are the shafts or plungers on the lower ends of which are placed the Rollers, Brushes, hard pieces of wood, slickers or other things which operate on the working board, to prepare, polish and finish the materials to be wrought, e.g. are the Rollers, Brushes, hard pieces of wood, slickers and other substances used and changed at pleasure, by any convenient mode of shifting them in the ends of the shafts or plungers for operating on and finishing the works.

K.K. are oblique beams, or shafts passing from the front top frame timber nearly at right angles with the working shafts or plungers, to support the spiral springs, N.N. The spiral springs, N.N. are provided to give to the working shafts or plungers, in the operation the necessary pressure, and relaxation of pressure while in operation and passing over the working board. The moveable working board P, slides from side to side under the working shaft, or plunger, so that the roller ^{other} at the lower end of the shaft, may work on the whole surface of the skin or other material to be finished, which when working on that board is fastened thereto. This board is moved as follows, a Ham i. at the end of the shaft I.I. plays on the spring j. which at every revolution, sinks the wire k on to and turns the wheel l, which is fastened on to one end of a shaft, at the other end of which under

the board F. is the cogged wheel - re. turning under a ratchet which is fastened to and moves the board F. by moderate degrees until it is entirely moved from under the shaft or plunger which operates over it. A catch is placed behind the wheel I. to prevent it from turning back while the spring K. is detached from the wheel L. Then the movable board has passed entirely by the shaft or plunger, or as far as the operator deems, any simple machinery may be applied to detach the catch and the spring K. at the same time from the cog of the wheel L. when the movable board will be carried back to its original station by a suitable weight attached by a line or strap to the cylinder or around which it runs, up and raising the weight while the movable board is prodding outward. By means of my combination of machinery an operator of common skill may with greatly increased speed and accuracy of work go through the process of softening, graining, boarding, polishing and finishing skins, hides &c used to make Morocco and other soft leather and all kinds of curried leather.

On testimony that the above is a true description of my said invention. I have hereunto set my hand this twenty third day of January in the year of our Lord one thousand eight hundred and thirty five

test.
